UNITED STATES PATENT OFFICE

AUBREY M. LEE, OF UNIVERSITY PLACE, TEXAS

ICE-MAKING SYSTEM

Application filed September 4, 1933. Serial No. 303,799.

This invention relates to new and useful improvements in ice making systems.

One object of the invention is to provide a system whereby the time of freezing and energy required for freezing are lessened to a substantial degree by bringing the water that is to be frozen into intimate contact with the freezing agent, together with means whereby the blocks of ice may be harvested from the bottoms of the containers, thus making for economy in time and labor both in the production and the harvesting.

A particular object of the invention is to provide means for freezing a block of ice and harvesting said block of ice from the bottom of the container, whereby said block may be more conveniently handled and more quickly removed and transported from the container.

20 A further object of the invention is to provide means for introducing air into the lower portion of each container and discharging the air at the top thereof.

25 A construction designed to carry out the invention will be hereinafter described, together with other features of the invention.

The invention will be more readily understood from a reading of the following specification and by reference to the accompanying drawings, in which an example of the invention is shown, and wherein:

30 Fig. 1 is a plan view of a system constructed in accordance with the invention,

35 Fig. 2 is a plan view of one of the units and associated parts,

Fig. 3 is a vertical sectional view of one of the units taken on the line 3—3 of Fig. 2,

40 Fig. 4 is an enlarged horizontal cross-sectional view taken on the line 4—4 of Fig. 3,

Fig. 5 is a perspective view of the air nozzle supporting bracket,

Fig. 6 is a sectional view of one of the containers showing the air hose connection,

45 Fig. 7 is a view, partly in section and partly in elevation, showing a block of ice in position on the truck and ready to be harvested.

50 Fig. 8 is a vertical sectional view of a portion of a modified form of container taken on the line 8—8 of Fig. 9, and

Fig. 9 is an underside view of said container.

In the drawings the numeral 10 designates a container or vat which is preferably cylindrical in shape. Rigidly mounted in the container are a plurality of upright ice or water cans 11 which are preferably cylindrical and are closely associated so as to economize in space. However, it is to be understood that the invention is not to be limited to a cylindrical can.

The upper and lower ends of the cans are extended beyond the top and bottom of the container, as is best shown in Fig. 3. The bottom of each can is open and is provided on opposite sides with inclined horizontal lugs or ribs 13. A countersunk cap 14 is telescoped into the bottom of each can and is provided with a marginal flange 15 carrying a suitable packing and engaging the bottom edge of the can so as to form a fluid-tight joint when the cap is fastened. Each cap has a plurality of up-standing keepers 16 adapted to engage over the lugs 13. The cap is inserted so that the keepers enter between the lugs and the cap is then rotated in a clockwise direction to cause the keepers to ride up the inclined surfaces of the lugs whereby the caps are fastened in place.

For the top of each can a flanged cover 17 is provided. Each cover has pins 18 for engaging in bayonet slots 19 in the upper end of the can, whereby the cover may be fastened in place. Suitable packing gaskets may be used on the covers.

55 In the bottom of each cap 14 is fitted a drain cock 20. Water may be supplied to the cans in any suitable manner, as by removing the covers 17 and inserting a water hose in the can. In one form of operation it is desirable to supply air to each can and exhaust the air from the can for the purpose of agitating the water and promoting the freezing operation. Each can is provided in its upper portion above the top of the container 10 with a nipple 21 on the inside of the can communicating with a tube 22 on the outside of the can. The tube is for the purpose of drawing air from the can as will be hereinafter explained. On the opposite side

of each can is provided a second nipple 23 communicating with a tube 24 which is connected with a line for supplying air.

A hanger bracket 25, as is best shown in Figs. 5 and 6, has upstanding arms 26 provided with apertures 27 for receiving the nipples 21 and 23. This bracket is provided at its center with a nipple 28 connected with a depending perforated air tube 29. As is best shown in Fig. 3, the tube 29 hangs in the can 11 so as to distribute the air. The nipples 23 and 28 are counterbored to receive spuds 30 on the ends of a hose or flexible tube 31, whereby the tube 24 is connected with the tube 29.

15 As an illustration of the freezing system I have shown a diagram in Fig. 1 wherein two groups of containers are shown. These containers are suitably enclosed in a housing 32, as is shown in Fig. 7.

20 For each group I provide a header 33 having laterals 34 extending to the tops of the containers 10 for exhausting the ammonia gas therefrom. Also for each group a header 35 is provided and connected with the bottom of each container by laterals 36 for supplying liquid ammonia. The liquid ammonia is supplied to the containers and comes into direct contact with the cans 11. Owing to the absorbed heat this liquid ammonia will 30 generate ammonia gas which will be carried off through the laterals 34 and the header 33.

For each group I provide an inlet header 37 and an outlet header 38. The tubes 24 are connected with the header 37 while the tubes 22 are connected with the header 38. The headers 37 are connected with an air supply pipe 39 extending from an air pump 40, while the headers 38 are connected with an air suction pipe 41 leading to the pump. 40 The air which is drawn from the cans 11 is re-delivered to said cans by the parts which have been described. The cans are never filled above the brackets 25 and, therefore, water can not be drawn into the tubes 22.

45 The ammonia gas headers 33 are each connected with a pipe 42 which in turn is connected with a suitable compressor 43. A T 44 is connected in the pipe 42 and a high pressure bypass pipe 45 is connected to said

50 T . The pipe 45 bridges the compressor and is connected in a discharge pipe 46 leading from the compressor. A cut-off valve 47 is connected in the bypass pipe and between this valve and the T 44 a suitable pressure valve 48 is connected in the pipe 45. The valve 48 may be of any suitable type such as is now in common use and which may be set to maintain a pre-determined pressure.

55 Each pipe 46 is connected with a suitable condenser 49 by means of a pipe 50. A return pipe 51 leads from the condenser to a receiver 52 and has a valve 53 adjacent said receiver. An auxiliary receiver 54 is connected with the pipe 51 by a short pipe 55 including a valve 56. Liquid ammonia is con-

tained in the receivers and this fluid, when escaping from the containers 10 through the tube 34, headers 33 and pipes 42 to the compressors, may be gaseous owing to the absorbed heat. Upon passing through the condenser the fluid is again reduced to a liquid state.

70 Each header 35 is connected with a branch pipe 57 including a valve 58, and these pipes are in turn connected with a supply pipe 59 having connection at its end with branch pipes 61 and 62. The pipe 61 is connected with the main receiver 52 and includes a cut-off valve 63, while the pipe 62 is connected with the auxiliary receiver and includes a 75 cut-off valve 64 and an ordinary pressure reducing valve 65. The liquid ammonia is thus supplied to the containers through the pipes 36 from the headers 35.

80 In operating the system the valves 47 and 48 are closed. Water is supplied to the cans 11 by removing the covers 17 and flowing the water through a hose or any other suitable manner. The air pump 40 being started will 85 create a suction, thus drawing air from the cans 11 through the tubes 22, headers 38 and pipe 41. The pump 40 will discharge air through the pipe 39, which air will be distributed to the laterals 37 and conducted by the tubes 24 through the connections 31 to 90 the nozzle tubes 29. The air will thus be discharged from the tubes 29 at various elevations.

95 The compressors 43 being in operation and the valves 64 and 65 being closed, liquid ammonia is discharged from the main receiver 52 through the pipes 61, 59 and 57 to the headers 35 from which it is conducted by the laterals 36 to the bottoms of the containers 10.

100 This liquid is circulated through the containers and around the water cans. Owing to the cylindrical shape of the containers and the water cans, the latter may be placed in close relation and yet sufficiently spaced to permit a free circulation around each can. Except for small portions at the upper and lower ends, the entire length of each can is 105 exposed to the contact of the liquid ammonia within the container.

110 The liquid ammonia coming in direct contact with the cans 11 will absorb the heat and the water in said cans will thus be cooled, as is well understood, the air agitation promoting the freezing operation. The liquid ammonia expanding in the containers is converted into a gas and this gaseous fluid is exhausted from the top of each container through the pipe 34.

115 These warm gases are conveyed by the pipes 34 to the headers 33 by reason of the suction created by the compressors. The warm gases are conveyed by the pipes 42 to the compressors 43 and after being compressed, whereby their temperatures are 120 raised, they are conducted by the pipes 46 to

the pipe 50 and thence to the condenser 49. The warm gases entering the condenser are converted into liquid ammonia and this is delivered by the pipe 51 to the containers 52 and 54.

5 When ice is produced in the cans 11 of group 1, a valve 66 in the pipe 42 is closed, thus cutting off the return of the ammonia fluid to the compressor of said group. The 10 pipes 42 of the two groups are connected by a cross pipe 67 including a cut-off valve 68, which is normally closed. Consequently when the valve 66 is closed and the valve 68 is opened, both compressors will draw the ammonia liquid from group 2. This will permit the harvesting of ice from group 1 without disturbing the operation of group 2.

By opening the valve 47 of the pipe 45 connected with compressor number 1, warm gas 20 is by-passed from the pipe 46 through the pipe 45 to the header 33 of group 1, thus reversing the flow. The reducing or pressure valve 48 is set to control the pressure and flow of this gas. For instance the gas may have a 25 temperature of approximately 110 degrees Fahrenheit and the valve 38 may be set to maintain the pressure about 110# gauge.

The warm gas thus introduced into the containers 10 of group 1 from the pipes 34 will 30 contact with the walls of the water cans and sufficiently heat the same to cause a slight thawing of the blocks of ice in said cans so that said blocks can be removed. At the same time the gas is condensed into liquid 35 ammonia. This liquid will flow out through the pipes 36 of group 1 to the header 35 and will be conducted by the pipe 57 to the inlet header 35 of group 2.

Should the condensation of the gas in 40 group 1 be insufficient to supply group 2 while group 1 is being thawed, the valve 63 in the pipe 61 of the main receiver 52 is closed and the valve 64 of the auxiliary receiver is opened, whereby an auxiliary supply of ammonia liquid is delivered to the pipe 59. The 45 valve 65 is set to maintain the proper pressure, as is obvious. It is to be understood that the invention is not to be limited to two groups, and the system may include any suitable number of groups.

The thawing of the ice in group 1 will require about twenty minutes, more or less; however, this time is subject to variation. Of course any other thawing method might be 55 used. In harvesting the ice from the cans it is necessary to first remove the covers 17 and then disconnect each hose 31 from the nipple 28 so that a hot needle or equivalent thawing tool may be inserted in the tube 29 to thaw the block of ice therefrom.

The principal feature of this invention is harvesting the ice from the bottom of the can. As is shown in Fig. 7 the cans are elevated above the floor 70 of the housing 32. 60 The cans are placed in such an elevation that

each block of ice when supported on a truck 71 will have its upper end extending into the lower end of its respective can. After the thawing operation the caps 14 are removed and the blocks of ice are lowered to the truck 70 75 71. Prior to removing the caps 14 it is advisable to replace the covers 17 so that the block in descending will tend to create a suction, whereby its descent will be retarded. Any suitable means for lowering the blocks 75 could be used if desired.

By leaving the upper ends of the blocks within the lower ends of the cans, it will not be necessary to replace the caps 14. The cans can be again filled with water and after the 80 freezing process has progressed to the proper degree the harvested blocks may be severed just below the cans and removed. Of course if desired the entire block could be harvested and the caps replaced. By harvesting the 85 blocks from the bottoms of the cans considerable time and labor, as well as expense, is saved.

It is not necessary to use the particular kind of cans and containers which have been 90 described, as the invention may be applied to any form of freezing can. In Figs. 8 and 9 I have shown a rectangular can 80 having a flanged cap 81 telescoping into its bottom. The cap has a marginal flange 82 carrying a 95 gasket 83 for engaging the bottom flange 84 of the can. Cross heads 85 have their ends engaging in hangers 86 and carry screws 87 engaging in bosses 88 arranged in the counter-sunk bottom of the cap. By tightening the 100 screws the caps are firmly fastened in position.

Various changes in the size and shape of the different parts, as well as modifications and alterations, may be made within the scope 105 of the appended claims.

What I claim is:

1. In an ice producing apparatus, a container for holding a refrigerant, a water can in said container, a removable bottom for the 110 can, whereby the block of ice may be harvested from the bottom of said can, and a removable cover for the upper end of the can sealed thereto to form a vacuum as the ice is withdrawn from the can.

2. In an ice producing apparatus, a container, water cans in said container having their upper and lower ends exposed, covers for the upper ends of the cans, means for introducing air into the upper ends of the cans, means for exhausting air from the upper ends of the cans, means for circulating a refrigerant through the container, and removable caps for the bottoms of the cans, 120 whereby the ice may be harvested from the bottoms of said cans.

3. As a sub-combination in an ice producing apparatus, a refrigerant container having an inlet and an outlet, a plurality of water 130

cans in said container having their upper and lower ends projecting from said container, removable covers for the upper ends of the cans, and removable caps for the lower ends of said cans.

5   In testimony whereof I affix my signature.

AUBREY M. LEE
